UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,162,865.

Specification of Letters Patent. Patented Dec. 7, 1915.

Application filed May 22, 1911. Serial No. 628,782.

To all whom it may concern:

Be it known that I, CHARLES J. KLEIN, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming 10 a part of this specification.

My invention relates to electric switches.

One of the objects of my invention is to provide an improved switch of simple and inexpensive construction.

15 A further object of my invention is to provide improved means for supporting and inclosing the parts of the switch mechanism.

Other objects and advantages of my improved construction will hereinafter appear.

In this application, I shall for purposes of illustration describe my invention as applied to a switch of the cleat type. My invention itself, however, is not limited in 25 its use to switches of this type or to the specific construction hereinafter described, but may be widely modified and used in various other relations if desired.

In the accompanying drawings I have 30 illustrated one form of a cleat switch constructed in accordance with my invention.

In the views of these drawings:—Figure 1 shows a longitudinal sectional view of the assembled switch device. Fig. 2 shows a top 35 plan view of the switch with a portion of the cover removed. Fig. 3 shows a transverse sectional view on line 3—3 of Fig. 2 with the cam member in elevation. Fig. 4 shows an interior view of the upper casing member. Fig. 5 shows a perspective view of the switch contactor. Fig. 6 shows a sectional view on line 6—6 of Fig. 2. Fig. 7 shows a perspective view of one of the stops for the switch mechanism.

45 In these figures I have shown a preferred form of switch mechanism which is of the push button type described in my Patent No. 985,421 patented February 28, 1911. This mechanism includes a reciprocating 50 cam member 1 of the conformation of a double frustum, positioned base to base, having flanges 2 at its reduced ends and oppositely extending push buttons 3 extending beyond the flanges. A movable contactor 4 is arranged to be reciprocated with

a quick snap action when the cam member 1 is reciprocated, to make or break an electrical circuit. This movable contactor 4 is preferably constructed of stamped resilient sheet metal and is provided with a body 60 portion 5 having rearwardly extending rounded shoulders 6 having projections 6^a and forwardly extending side pieces 7, bent substantially at right angles to the body portion 5. In a preferred form the edges 65 of these side pieces 7 are slightly peaked and bent outward, as shown in Fig. 5. The side pieces 7 carry between them and adjacent their ends at a distance from the inner surface of the body portion 5, a vertically 70 extending spacing strip 8, preferably of the same material as the body portion. This spacing strip is provided at its corners with shoulders 9 adapted to engage in vertically 75 extending slots 10 in the top and bottom edges of the sides 7. Both the body portion 5 and the spacing strip 8 are provided with central perforations 11 of a sufficient size to permit the cam member 1 to pass through the same. The contactor is arranged to ride upon the cam member as shown in Fig. 2 and carry between its body portion 5 and the spacing strip 8 a garter 80 spring 12 which grips the cam member. In order to provide sufficient room for the garter spring to expand when moving over the crest of the cam, slots 13 may be cut in the opposite sides of the side pieces 7 of the contactor, between the body portion 5 and the spacing strip 8. In order to facilitate 85 the bending of the side pieces 7, notches may be cut in the same as illustrated at 14. This contactor 4 is arranged to bridge the contact surfaces of terminal members 15 and 16 which are carried by a base 17 of 90 substantially rectangular shape and cross section. As shown in Fig. 2 the terminal members 15 and 16 are preferably of a similar construction but are oppositely disposed and arranged to be fixed to the base 17 in a preferred form by screws 18 which extend through the base and are accessible from the under side of the same. In a preferred form these terminals 15 and 16 are 95 mounted in similar correspondingly shaped recesses 19 in the upper surface of the base 17 and are provided with reduced necks 20 and upwardly extending V-shaped contact members 21, which are preferably bent up from the body portion of the terminal mem- 100

bers, substantially at right angles to the same. In a preferred form these contact members are provided with elongated contact surfaces 22, slightly peaked at 23 and 5 provided with downwardly extending projections or shanks 24 whose lower ends bear against the bottom of a central rectangular shaped recess 25 in the upper surface of the base 17. In this recess 25 the switch mechanism heretofore described is arranged to 10 reciprocate and is supported in stops 26 and 27 mounted upon the bottom at the opposite ends of the recess 25. These stops are provided with feet 28 and 29 which rest upon 15 the bottom of the recess 25 and are secured to the same by screws 30 and 31 extending through to the bottom of the base member 17 and having their heads housed in suitable recesses 32 and 33. These stops 26 and 27 20 are on opposite sides of the base 17 in the opposite ends of the chamber 25 and are arranged in a plane between the contact faces of the terminals 15 and 16.

Perforations 34 and 35 are provided in the 25 vertical portions of the stops which are adapted to permit the push buttons 3 of the switch mechanism to be reciprocated, but which are not of a sufficient size to permit the flanges 2 to pass through the same. 30 When the cam member is reciprocated across the base the inner surfaces of the stops 26 and 27 therefore serve to establish the limits of the movement of the cam member. As the cam member is moved across the base 35 its crest passes through the garter spring 12 and this garter spring is expanded to throw the contactor to one of the limits of its travel. One limit of the travel of the contactor is established by the engagement of 40 the contactor with the contact surfaces of the terminal members 21. When the contactor moves toward the terminal members, the out-turned edges of the same engage the outer sides of the contact surfaces 22 with a 45 wiping contact which continues until the spacing strip 8 of the contactor abuts against the peaked edge of the contact members 21. The other limit of the travel of the contactor is established by the stop 26, which 50 not only serves the function of providing a stop for the cam member and a guide for the push button, but also is of such a construction as to permit it to provide a stop for the contactor. This is accomplished by 55 providing it with a horizontally extending bent portion 36, which extends toward the contactor, as illustrated in Figs. 2 and 3. Laterally extending ears 37 are formed on the portion 36 and a forwardly extending 60 lug 38, having slanting sides 39, is also preferably provided. Thus it is seen that when the contactor is brought back to open circuit position the back of the contactor, which is the body portion 5 as shown in Fig. 2, 65 and the rounded shoulders 6 may engage the

adjacent edges of the ears 37 and the lug 38. In a preferred form, however, I so shape the lug 38 that it is not of a sufficient length to strike the body portion of the contactor. Consequently the impact is received on the 70 projections 6^a on the contactor, which are better able to withstand the shocks. In a preferred form I provide the foot or pedestal 28 of the stop 26 with ears 40 and a lug 41, corresponding to the ears 37 and the lug 38, 75 so that both ends of the contactor will engage stops substantially at the same time and all strain upon the parts be thus obviated. In a preferred form I may strike up the ears 40 on the foot 28 as shown in Fig. 80 7. Further, in order to seat the stop 26 securely in the base member 17 I may provide the pedestal 28 with punched out tongues 43 which may be received in rectangular shaped recesses 44 in the base 17 on 85 opposite sides of the screw 30.

The outer ends of the terminal members 15 and 16 are enlarged as shown at 45 and provided with binding screw 46 and oppositely extending ears 47 to facilitate the connections of the conductors to the binding screws. Leading to the binding screws 46 are transversely extending grooves 48 in the upper surface of the base 17 which are adapted to receive the conductors. Perforations 49 communicating with the binding screws through shallow recesses 50 permit the conductors to be brought through the bottom of the base 17 to the binding screws if desired. The base may also be provided with vertically extending perforations 51 having reduced portions 52 at their lower ends, so that screws may be inserted in the base to attach the same to any suitable support. If desired, feet 53 may be arranged 105 in suitable positions on the bottom of the base member.

A switch cover 54 is adapted to be clamped over the top of the base member 17 by screws 55 arranged on opposite sides of the switch 110 mechanism as shown in Fig. 2. These screws 55 preferably have their heads set in recesses 56 in the upper surface of the base and extend downward through suitable recesses to 115 taps 57 riveted to the base 17 and sealed in the same at 58, in such a manner as to prevent their rotation or the loss of the same. If desired insulating washers 59 may be carried by the screws 55. The inner surface of the cover 54 is provided with a central chamber 60 of substantially rectangular cross section, which is provided at its opposite ends with connecting recesses 61, arranged to house the stops 26 and 27, and 120 grooves 62 arranged to permit the reciprocation of the push buttons 3. As shown in Fig. 4 the portion of the casing above the contact members 21 is cut off obliquely as at 125 63 to receive these contact members. Communicating with the central recess 60, in the 130

cover 54, are laterally extending recesses 64 of a sufficient size to permit the entry of the conductors to the binding screws 46, and communicating with these recesses 64 through grooves 65 are transversely extending grooves 66 corresponding to and registering with the grooves 48 in the upper surface of the base member 17. In a preferred form both the base 17 and the cover 54 are 10 provided with walls 67 around their edges as shown in Figs. 1 and 2, and are composed of an insulating material such for example as porcelain or molded stone.

When the parts of the assembled switch 15 are in the position shown in Fig. 2 the switch is in open circuit position. In order to operate the switch the lower push button 3 would therefore be pushed upward. The garter spring 12 then expands and as soon as it 20 passes over the crest of the cam 1 it throws the contactor 4 to the circuit closing position wherein it bridges the contact members 21. In moving to this position the edges of the out-turned sides 7 of the contactor 4 25 engage the outer sides of the contact members 21 with a wiping action and move along the same until the front surface of the spacing strip 8 abuts against the forward edges of the contact members 21. Then the switch 30 is in circuit closing position and the circuit is complete between the binding screws 46. When it is desired to move the switch to open circuit position the upper push button 3 is pushed downward to throw the contactor 4 to the position shown in Fig. 2. In 35 this position the projections 6^a on the contactor abut against the lugs and ears provided on the stop 26. In the circuit closing position the edges of the stationary contacts 21 engage the contactor 4 approximately at its center line and in the circuit open position the contactor 4 is engaged at its top and bottom. Thus it is seen that the strain 40 upon the contactor is reduced to the minimum. Further, the parts are so constructed and arranged that when the contactor reaches the circuit closing position the opposite end of the cam member abuts against a stop and when the contactor reaches circuit open position the other end of the cam member abuts against its stop. Thus it is 45 seen that all strain upon the parts is removed. Further, due to the improved construction of the contact members there is little or no sparking at the contacts, and 50 due to the use of my improved switch mechanism the circuit is made or broken very quickly, with very little opportunity for 55 sparking. By the use of the resilient contactor and the improved construction of the contacts the shock or jar in the operation of the switch mechanism is very small. Further, by the provision of the improved means 60 for permitting the entry of the conductors 65 and the passage of the same through the

switch casing the switch may be very readily placed in position and the conductors very readily connected to its terminals. Further, the parts of the switch mechanism are readily accessible by merely loosening the 70 screws in the cover and removing the latter, and the parts of the switch mechanism are carefully insulated from each other so that there is no possibility of any short circuits within the switch. 75

In the foregoing description of the specific construction illustrated in the drawings I have not attempted to indicate all of the equivalent constructions and modified forms in which my invention may be incorporated. 80 I have instead, however, restricted myself to a description of this particular form, believing that it is readily evident to those skilled in the art that my invention may assume various other forms and be widely 85 modified. Consequently I do not wish to be limited to the specific construction herein described, but rather wish to cover all of the various forms and modifications which fall within the scope of my invention. 90

What I claim as new and desire to secure by Letters Patent is:—

1. In an electric switch, a contactor comprising a sheet metal member having a body portion and parallel resilient portions at 95 right angles to said body portion, and a spacing strip held in loose connection with said resilient portions and removed from said body portion.

2. In an electric switch, a contactor comprising a sheet metal strip having a flat intermediate portion and rearwardly looped and forwardly extended resilient contact arms, and a spacing strip removably clamped between said arms and parallel to 105 said body portion, said strip and said body portion having aligned apertures.

3. In an electric switch, a snap switch mechanism including a reciprocable cam, a sheet metal contactor, a base upon which 110 said switch mechanism is supported, terminal contacts having peaked edges carried by said base in a plane substantially at right angles to said base and extending into the path of said contactor, and means for 115 guiding said cam member and limiting the movement of said cam member and said contactor.

4. In an electric switch, a base, a snap switch mechanism carried thereon, and 120 means for limiting the movement of the parts of the switch mechanism including a stamped metal stop having a central perforation through which one of the operating members of said switch mechanism extends 125 and stamped ears arranged to engage the other of said operating members of said switch mechanism to limit its movement.

5. In an electric switch, a base, a snap switch mechanism including a cam and a 130

movable contactor, and means for limiting the movement of said contactor including a stamped metal stop having a perforation through which a portion of said cam member extends and an extension substantially at right angles to its body portion provided with ears arranged to limit the movement of said contactor.

6. In an electric switch, a push button snap switch mechanism, means for limiting and guiding the movement of the operating parts of the same including a stamped metal stop having extensions substantially at right angles to its body portion arranged to engage one of the parts of said switch mechanism and a central perforation in its body portion arranged to permit a portion of one of the operating members to extend therethrough and be limited in its movement by engagement with the edges of said perforation.

7. In an electric switch, a base, a push button snap switch mechanism carried thereon and a combined stopping and guiding member for said switch mechanism removably mounted on said base and seated in recesses therein, said member being provided with projections arranged to engage said recessed base and one of the parts of said switch mechanism.

8. In an electric switch, a push button snap switch mechanism, terminal contacts therefor arranged on opposite sides of the same, a base on which said terminal contacts are carried, and a combined stop and guide for said switch mechanism arranged to guide and limit the movement of one of the parts of said mechanism and to establish one limit of travel of one of the other parts of

said mechanism, said stop being removably mounted in recesses in said base and having stamped members arranged to engage with said base and with one of the parts of said switch mechanism.

9. In an electric switch, an integral contactor having a sheet metal body portion provided with rearwardly extending rounded shoulders on its opposite sides and forwardly extending contact arms, and a spacing strip between said arms locked into engagement therewith, said spacing strip and said body portion being provided with registering perforations.

10. In an electric switch, a contactor including a stamped metal body portion having contact arms bent substantially at right angles to said body portion and having peaked out-turned edges and a spacing strip between said arms arranged in a plane parallel with said body portion, said spacing strip and said body portion being provided with substantially registering perforations.

11. In an electric switch, a reciprocable cam; a spring arranged to grip the surface thereof, a movable contactor in which said spring is housed having perforations through which said cam is arranged to be reciprocated, said contactor being provided with perforations to permit the expansion of said spring when said cam is moved.

In witness whereof, I have hereunto subscribed my name in the presence of two witnesses.

CHARLES J. KLEIN.
